UNITED STATES PATENT OFFICE

WILLIAM THOMAS BUCKINGHAM ROBERTS, OF LEICESTER, ENGLAND, ASSIGNOR TO
UNITED SHOE MACHINERY CORPORATION, OF PATERSON, NEW JERSEY, A CORPORA-
TION OF NEW JERSEY

TAPE APPLYING MACHINE

Application filed February 17, 1928, Serial No. 255,170, and in Great Britain March 14, 1927.

This invention relates to machines for laying reinforcing tape upon sheet material of any kind, but particularly upon the parts of shoe uppers.

An object of the invention is to improve machines of this class in respect to operating efficiency and speed, mechanical construction and range of usefulness. In this endeavor, I have improved certain of the instrumentalities of tape laying machines and combined them in novel manner with each other.

Among other features, there is provided, in combination with a work support and tape feeding and pressing instrumentalities, an improved guiding mechanism for leading the tape to the work, designed particularly to facilitate laying the tape about curves. To this end, the tape guide as herein illustrated is mounted for rocking movement about an axis which is longitudinal with respect to the direction in which the guide leads the tape.

In order to facilitate the tape severing operation, the tape is tensioned at the completion of a taping operation, and to this end the delivery end of the guide is moved between the tape feeding and pressing instrumentalities, causing the tape to be drawn about the latter.

Another feature consists in a novel feeding foot, having a portion for engaging the work, and a tape-engaging portion arranged to act upon the tape at one side of the line of work feed. A foot of this description has been found to operate with particular advantage on heavy and medium work. Its range of usefulness is extended to delicate work by arranging the work-feeding portion thereof to be rendered inoperative when desired, so that the work will be fed only by the tape-engaging portion acting through the superposed tape.

Another feature of the invention consists in novel severing mechanism for the tape, including a knife the operation of which is effected by a means which first moves the knife bodily toward the tape and then imparts to it a severing stroke extending widthwise across the tape. Invention is also to be recognized in the provision, in the illustrated con-

struction, of means for moving the knife from an inoperative position, toward which it is resiliently urged, to a position of readiness for its cutting stroke prior to a taping operation. Preferably, the knife is maintained in inoperative position by a treadle mechanism, which forms another feature of the invention, and as herein illustrated is constructed and arranged to actuate the knife during its cutting stroke.

Other features of the invention consist of a work support of two parts, one of which is arranged to move with the feed foot during the feeding movement and is subsequently returned to its initial position, and also of a combination wherein a work support as above described is associated with a single controlling treadle by the operation of which the work support is retracted from a position in which it presents the work to the operating tools and simultaneously causes the knife to cut the tape.

My invention will be best understood and appreciated from the following description of a preferred embodiment thereof, selected for purposes of illustration and shown in the accompanying drawings, in which

Fig. 1 is a view of the machine in front elevation, certain parts being broken away;

Fig. 2 is a view in end elevation, partly in section;

Fig. 3 is a view in end elevation, partly in section, of parts of the starting and stopping mechanism;

Fig. 4 is a view in end elevation of the operating instrumentalities of the machine;

Fig. 5 illustrates the hammer cam and the parts operated thereby;

Fig. 6 is a view in end elevation of the tape severing knife and associated parts and

Fig. 7 illustrates an alternative form of feed foot.

The illustrated machine comprises a base 1, having an upstanding column 3 at its right end which carries the starting and stopping mechanism of the machine and merges into an overhanging arm or bracket 5, carrying at its outer end the operating instrumentalities of the machine. At its left end, the base 1 is provided with bearings for a work-sup-

porting post 81 upon which the work is presented to the action of the instrumentalities carried by the overhanging arm 5.

Mounted in bearings in the arm 5 is a horizontally disposed driving shaft 7, having secured to its outer end a hand wheel 9 secured to a brake drum 10 having a ring 11 which constitutes a flat clutch face. A driven pulley 13, carrying a clutch disk 15, is mounted for free rotation upon a sleeve 17 which is free to move longitudinally upon the shaft and constantly urged by springs 19 toward the right into clutching engagement with the clutch ring 11. The sleeve 17 carries a collar 21 and a cam disk 23, having a cam 25 upon its right hand or inner face.

A clutch operating lever 31 is pivotally mounted upon a boss projecting from the column by means of a shaft 33, extending parallel to the driving shaft 7. A spring 34, interposed between the column 3 and the lower end 35 of the clutch lever, acts to press the upper end of the same inwardly. The lever 31, at its upper end, carries a roll 37, rotatable on a transverse axis and adapted to be located between the collar 21 and the cam disk 23 of the sleeve 17 when the upper end of the lever 31 is swung inwardly. Under these circumstances, the roll 37 cooperates with the cam 25 to shift the sleeve 17 toward the left and disengage the clutch. When the upper end of the clutch lever 31 is moved outwardly, the roll 37 is removed from the path of the cam 25 and the sleeve is free to move toward the right under the actuation of the springs 19 to engage the clutch and start the machine.

The clutch lever 31 is under the control of a clutch treadle, connected to a vertical treadle rod 41, having at its upper end a wedge cam 43 adapted to cooperate with a cam roller 45 on the upper end of the clutch lever 31 to swing the lever outwardly when the treadle rod is depressed. Upon the release of the treadle, the clutch lever 31 is returned by its spring to initial position and, at the proper point in the cycle of the machine, the clutch disengaged as already described.

Simultaneously with the release of the clutch, a brake is applied to the brake drum 10. This comprises a brake block 57, mounted upon the right-hand end of an arm which extends over the brake drum and is provided with a depending arm 59, as shown in Fig. 3. The arm 59 carries at its lower end a roller 65, which is mounted on a roll-carrying pin 61 having an eccentric bearing for the roller, which supports the roller in position between the collar 21 and the cam disk 23 of the sleeve 17. The arm 59 is swung to apply the brake block to the brake drum whenever the sleeve is moved into clutch-disengaging position. The eccentricity of the pin 61 affords provision for adjustment of

the arm 59 relatively to the collar 21 and cam disk 23, so as to compensate for wear or in the preliminary setting up of the machine. In order to rotate the pin 61, a toothed segment 67 is secured to the rear end of the latter and arranged to mesh with a pinion formed in the rear end of a transverse shaft 55, which carries at its front end a knurled head 69 by which the shaft may be rotated. A set screw 71 is provided for holding the shaft 55 in position corresponding to any adjustment of the segment 67.

Adjacent to the cam 25, the clutch lever 31 is provided with a finger 47, adapted to cooperate with a controlling lever 49 pivotally mounted upon a pin 50 extending between ears projecting from the frame of the machine and spring-pressed downwardly at its front end. Thus when the upper end of the clutch lever 31 is moved outwardly, the controlling lever 49 moves downwardly to prevent inward movement of the clutch lever 31 until the movable stop is swung upwardly again. This is effected through a roll 51, carried by the controlling lever 49 and cooperating with a peripheral cam face 52 upon the cam disk 23. The cam face 52 is so shaped that the clutch can be disengaged only when the instrumentalities of the machine are in the proper position in their cycle, that is to say, when the hammer is down and the combined feed foot and tape sealing foot is raised. In order that the shaft 7 may be released when the clutch treadle is depressed, should this be desired, a hand-operated lever 53 is mounted upon the right end of the shaft 33 and arranged to contact with the cam 25 to force the sleeve 17 toward the left and so hold the clutch disengaged. The hand-operated lever is held by a friction clutch in any position to which it is moved by the operator.

The work-supporting post 81 is mounted for limited vertical movement in the base 1 of the machine and held normally in its lowermost position by its own weight. In this position, a collar 83 on the post is seated in a recess in the base, as clearly shown in Fig. 2. In order to move the post upwardly, a treadle is connected by a treadle rod to one arm 85 of a bell crank lever, the other arm 89 of which is formed with a cam that contacts with a roll 87 connected with the lower end of the post. The outer portion of the cam arm 89 is concentric and supports the post 81 in a stationary condition when the treadle rod is depressed to carry the face 91 of the arm 85 to the bench.

The roll 87 is not carried directly by the work-supporting post 81 but is mounted on the lower end of a vertical sleeve 93, which surrounds the lower reduced end of the post and sustains the downward pressure of the post transmitted through a spring 95 which is seated against the upper end of the sleeve 93 and the under side of the collar 83. A

transverse pin 97 which projects through the post and into slots in the sleeve limits relative axial movement of the sleeve 93 and the post 8. A thumb screw 99, shown in Fig. 1, is adapted to contact with the collar 83 of the post and limit the upward movement thereof, so that after the treadle has been depressed to move the sleeve 93 and spring 95 bodily upwardly carrying the post to its operative position, as determined by the adjusting screw 99, the spring 95 will yield and permit lost motion of the sleeve 93. The spring 95 is sufficiently strong to support the post 81 in operative position against the pressure of the operating instrumentalities of the machine.

The upper end of the post 81 carries a work-support which comprises two parts, a fixed rear part or anvil 101 and a rocking part or support 103. The anvil is convex in contour and located substantially beneath the hammer of the machine, although its front edge may be slightly in advance of the front edge of the hammer and immediately underneath the tape severing knife, to be described hereinafter. The rocking support 103 of the table is formed upon a finger 105, pivoted to oscillate upon a transverse axis and is located with its work-supporting face under the feed foot of the machine. The finger 105 is normally pressed forwardly against a stop by a compression spring 107. When the rocking support is moved forwardly in the feeding operation, its top surface will be substantially horizontal and flush with the top front edge of the stationary anvil 101.

In operation, the feed foot 141 descends and presses the work on top of the rocking support 103. It then moves rearwardly, carrying the work and the rocking support with it and then rises to release the work, whereupon the rocking support 103 slides under the work to its initial position under actuation of the spring 107 and is in readiness for the next feeding step. For handling some classes of work, the surface of the anvil or the rocking support, or both, may be covered with or formed of rubber.

Mounted upon the right side of the post 81, as viewed in Fig. 1, is an edge guide 109 which is carried by a supporting member 111, pivoted to the post 81 upon a transverse pin 113 in such a manner that it can be swung downwardly into inoperative position when not in use. As shown in Fig. 1, the supporting member 111 is held in operative position by the latch 115.

In the outer or left-hand end of the overhanging arm or bracket 5 are mounted the operating instrumentalities of the machine, which comprise briefly, a heated hammer 121, a work-feeding foot 141, a tape feeding and sealing foot 161, a tape guide 171 and a tape severing knife 191.

The heated hammer 121 acts by repeated blows upon the tape to cause it to adhere

properly to the work. As shown in Fig. 4, this is formed with a barrel 123 which contains an electric heating unit suitably connected and controlled. At its lower end, the hammer is provided with a foot 125 of curved contour, wide enough to cover the widest tape to be used in the machine and long enough to act several times on each piece of tape being fed beneath it. The barrel 123 of the hammer is connected to the head of the machine by two pair of parallel links 127 and 129, so that as it is moved up and down its path, which is short, is substantially in a straight line. The barrel 123 is provided with a lateral extension 131, carrying a hardened contact stud 133 which cooperates with an ear 135 projecting from the face of a yoke cam 137, as shown in Fig. 5. The yoke cam 137 is pivoted to the head of the machine by the same pivot that carries the upper links 129 and embraces the hammer cam 122 on the main shaft 7. As will be apparent, the hammer is moved upwardly by the action of the cam. It is moved downwardly in a yielding manner by a compression spring acting through the pin 138 which bears upon the lateral extension 131 of the hammer barrel. Compression of the spring may be regulated and controlled by a thumb nut 139 passing upwardly through the head of the machine within convenient reach of the operator. As already noted, the working face of the hammer is curved to correspond to the curve of the convex anvil and it is also corrugated or roughened. The hammer, as will be apparent, is the last of the instrumentalities of the machine to operate upon the tape and its function is to secure complete and uniform adhesion of the tape to the surface of the work.

The main shaft 7 carries near its left-hand end, as seen in Fig. 4, three cams, a lifting cam 142 for the work feed foot, a feed cam 144 to give the feed foot its feeding movement, and the hammer cam 122, already described. In front of the hammer 121 and spaced somewhat therefrom is the work-feeding foot 141, which comprises a hardened feed dog 143, corrugated in its acting face and adapted to act upon the work at one side of the tape, not engaging the tape at all. The feed foot 141 is mounted upon the lower end of a plunger 145 which is received in vertical bearings in a feed foot casing member 147, pivotally mounted at its upper end upon a pin 149 to the frame of the machine. The member 147 is provided with a substantially rectangular opening 151, within which is located the feed cam 144. The upper part of the plunger 145 is connected to an operating extension or lip 153 by means of a web that passes out through a slot in the casing member 147. The lip 153 overlies the lifting cam 142, the action of which is opposed by a compression spring acting through a pin 155, the initial stress in which spring is controlled

by a thumb screw 157. The whole arrangement is such that upon the rotation of the shaft 7, the feed foot 141 is urged downwardly by the above-mentioned spring to grip the work, is then carried rearwardly or toward the left with a feeding movement by the cam 144, and is then moved upwardly and toward the right to its initial position by the combined effect of the cams 144 and 142, the 10 complete path being an ellipse with a flattened lower side.

The work-feeding foot 141 carries also the tape-feeding foot 161, which comprises a bar extending substantially the full width of the 15 work-feeding foot and having its acting face corrugated or roughened. The bar is carried upon the lower end of a vertical slide 163, mounted in a vertical guideway in the left-hand face of the work-feeding foot, and is 20 pressed downwardly by a spiral spring 165 against co-acting stops carried by the work-feeding foot. When in its lowermost position, the work-feeding face of the tape-feeding foot 161 is flush with or slightly below the 25 work-feeding face of the work-feeding foot 141.

In order to lead the tape into the proper position, a tape-guiding tube 171 is provided. This tube has a cylindrical shank 173 and is 30 mounted for rocking movement about its longitudinal axis in a carrier member 175, which itself is pivoted at its upper end upon a transverse pin 177 retained in a horizontal slot 179 (Fig. 2) in a bracket 181 carried by 35 the head of the machine. Since the tape passes longitudinally through the guide 171, the above-mentioned axis about which the tube is mounted for rocking movement is also longitudinal with respect to the direction in 40 which the guide is constructed and arranged to guide tape. The pin 177 is normally pressed rearwardly or toward the left by a spring, not shown. The rear lower end of the tape guide 171 passes to one side of and 45 close to the work feed dog 143 and is held in correct vertical position by the tension on the tape, the rear lower end of the guide being closely adjacent to the tape-feeding foot 161. The provision for axial rocking movement 50 of the tape guide has been found particularly useful in laying tape upon the work in a curved path.

For the purpose of cutting the tape at the completion of the tape-laying operation, means are provided which will now be described. These include a thin bladed knife 191, as shown in Fig. 6, which is located immediately in front of the hammer 121 and immediately in the rear of the tape-feeding foot 161. The knife blade is arranged to move in its cutting stroke with a draw cut in a direction widthwise of the tape across the work support from left to right, as viewed in Fig. 1. The blade 191 is carried in the lower end of a bent lever 193, which is piv-

oted for swinging movement upon a pin 194 to a cover plate 8 or cap which closes the end of the arm 5 of the machine frame.

Adjacent to the pivot 194 of the lever 193 is a vertically movable plunger 195, mounted in a tubular casing 196 and normally held in elevated position by a compression spring 197. The plunger 195 carries at its lower end a small roll 199, located in a cam groove 201 in the body of the bent lever 193, the arrangement being such that upon depression of the plunger 195 the knife will move from left to right to cut the tape. As shown in Fig. 6, the plunger 195 is depressed and the blade 191 occupies its final position in its cutting stroke. In order that the point of the blade may be normally clear of the work and the tape, the pin 194 of the knife holding lever 193 is located in a vertical slot in the cover plate 8 so that on depression of the plunger the knife is first moved downwardly toward the tape and thereafter toward the right widthwise of the tape. The spring 197 which elevates the plunger 195 also elevates the bent lever 193 to initial position in which the pin 194 engages the upper end of the vertical slot.

The knife is connected to a treadle of the machine in such a manner that release of the treadle will automatically cause the knife to operate. Overlying the head 198 of the plunger 195 is one end of a lever 203 (Fig. 1) which is pivoted upon a pin 205 to the overhanging arm 5 of the frame. The other end of the lever 203 carries a cam roll 207 which overlies a rocking cam 209 formed on one arm 211 of a bell crank lever pivoted upon the arm 5. The other arm 213 of the bell crank lever is connected, through a treadle rod 214, to the treadle which operates the work-supporting post 81. A spring 215 (Fig. 1) serves normally to hold this treadle raised. The arrangement is such that the knife plunger is normally held down when the treadle is raised, as shown in Fig. 1. When the treadle is depressed to raise the work support, the cam 209 is moved so as to permit the plunger 195 to rise and swing the blade to the left, as seen in Fig. 6, into a position in which it is ready to cut. At the end of the operation when the work support treadle is released, the knife plunger is immediately depressed and the knife actuated to sever the tape. The cam 209 and its connections are so designed as to cause the severing operation to occur before the work support has begun to drop. Thus the operator can sever the tape while the machine is running and the severed end may be laid upon the work before the support drops.

It is desirable that the tape should be firmly held in the cutting operation. It will be understood that when the machine stops, the hammer 121 is in its lowermost position so that it holds the tape to the work at a point

beyond the path of the severing knife. To hold the tape at the other side of the knife, mechanism is provided which will now be described.

5 Mounted in bearings in the side of the overhanging arm 5 is a horizontal shaft or spindle 221 (Fig. 1) carrying at its right-hand end an arm 223 which is held by a coil torsion spring 225 against a lip 227 projecting upwardly in the clutch lever 31. This arrangement is such that when the upper end of the lever 31 is moved outwardly in starting the machine, the shaft 221 is rocked so as to move outwardly the lower end of an arm 10 229 fixed to and depending from its left-hand end. The arm 229 carries a flat U-shaped member 231 which embraces a roll 233 on the upper end of an arm 235, the lower end of which is pivoted to the tape tube carrier 15 member 175. The upper end of the member 235 has a lug that projects into a vertical slot in the bracket 181. The arrangement is such that when the clutch is disengaged in bringing the machine to rest, the arm 229 20 will automatically rock the tape tube about its transverse pivot 177 to raise the lower end of the tube and so force the tape upwardly against the toothed under surface of the tape feed foot 161. The teeth on the surface 25 of the latter are directed against movement of the tape in the direction which would be caused by the cutting strain of the knife. The work-feeding foot 141 is raised from the work 30 at this time, as is also the tape-feeding foot 35 161.

The shaft 221 has pivoted upon it a tape-clamping arm 241 which is normally pressed by a torsion spring 243 in a direction to clamp, at its lower end, the tape against a ledge or projection on the bracket 181. When the machine is started, a pin 245 on the arm 229 lifts the clamping arm 241 and frees the tape. Thus when the machine is stopped, the tape 40 is held by the hammer and the tape-clamping arm 241 and is stretched across the tape-feeding foot by the lifting movement of the tape tube 171 and thus tensioned, ready for the severing operation by the blade 191. The arm 229 has fixed to it a finger lever 230 by 45 which it can be operated, if desired, independently of the treadle so that the tape can be released for adjustment without starting the machine.

The tape is mounted upon a reel, not shown, 50 which may be located wherever convenient to lead the tape downwardly, first to a slot in the upper end of the bracket 181, then between two lateral guide flanges projecting forwardly from the frame, then over a horizontal guide roll 188 located between the flanges and upon the pivot pin 177, then through the tubular guide 171, under the tape-feeding foot 161 and finally under the hammer 125. When the machine comes to 60 rest at the end of the taping operation, the

tape stretches between the front edge of the hammer, where it is held to the work and the horizontal guide roll 188 at an angle to the horizontal of about thirty degrees.

The operation of the machine will be apparent from the foregoing description but may be summarized as follows. When the machine has been stopped normally by raising the clutch treadle, it comes to rest with the hammer down and the work-feeding foot 70 141 elevated and in its right-hand position. If taping is to start from within the margin of the work, then the work is inserted in the machine above the anvil before elevating the work support. Thereafter, the post 81 is lifted to press the work, by means of the anvil 101, against the under side of the hammer 121. If taping is to start from the edge of the work, it may be preferred to raise the work support 75 first and then to insert the work in the machine with its rear edge against the front of the hammer and resting on the top front edge of the anvil. The clutch treadle is then depressed, whereupon the clutch lever 31 acts first to cause movement of the tape-clamping arm 241 forwardly to release the tape and thereafter to cause the clutch to engage and the driving shaft 7 to be operated.

The work-feeding foot and the tape-feeding foot now descend and the tape-feeding foot 80 161 acts to seal the free end of the tape to the surface of the work. The work-feeding foot and the tape-feeding foot then move toward the left, advancing the work and tape within range of the hammer 121 which 85 has been heretofore elevated out of engagement with the work. The hammer then descends and the work-feeding foot is elevated in returning to initial position. At the finish 90 of the taping operation, the clutch is disengaged and the machine stops with the hammer down so as to grip the work and tape upon the anvil 101, and at the same time the tape-clamping arm 241 is permitted to move inwardly and clamp the tape. The tape tube 191 is then rocked to stretch the tape across 95 the feed foot. On the release of the work support treadle, the knife 191 operates to sever the tape and the anvil drops to release the work. When the machine is re-started, the tape tube 171 rocks into normal position and that small amount of tape which was 100 located beneath the tape-feeding foot 161, or wrapped around the foot, is carried into a position in which it will be acted upon by the tape-feeding foot in its first stroke, so as to seal the tape to the surface of the work preparatory to a new taping operation.

It has been found that upon certain classes 105 of very light work, it is advantageous to dispense with the separate work-feeding foot and to feed both the work and the tape by the same instrumentality. To this end, there is disclosed in Fig. 7 an alternative form of feed foot 341 and tape-feeding foot 361 which 110

will now be described. In this construction, the work-feeding foot 341 is carried as in the construction previously described upon the lower end of the plunger 145. The feed dog 343 is pivoted by a pivot pin 301 to the feed foot 341, a spring 303 holding the feed dog downwardly so that an arm 305, projecting therefrom, contacts with and is positioned by a stop 307. The stop 307 has a flat side which 10 locates the feed dog in operative position and a curved side which may be made operative to swing the arm 305 in a clockwise direction, so as to lift the feed dog 343 and hold it out of contact with the work. In this case, 15 the feeding is effected by means of the tape-feeding foot 361 only and in this case the tape-feeding foot is formed as a part of the work-feeding foot 341.

Having thus described my invention, what 20 I claim as new and desire to secure by Letters Patent is:

1. A tape laying machine, having in combination, tape feeding and pressing instrumentalities, and an elongated tape guide 25 mounted for rocking movement about an axis which is longitudinal with respect to the direction in which the guide is constructed and arranged to guide tape.

2. A tape laying machine, having in combination, tape feeding and pressing instrumentalities, a tape guide the delivery end of which is movable between said feeding and pressing instrumentalities transversely to the direction of tape feeding movement to tension 35 the tape to facilitate cutting thereof, and means for thus moving said tape guide.

3. A tape laying machine, having in combination, a work support, a tape feeding foot, said support and foot being mounted for 40 movement toward and away from each other, and a tape guide for leading tape to said foot, said guide being movable to draw the tape about the feed foot when the latter and the support are separated at the conclusion of a 45 taping operation.

4. A tape laying machine, having in combination, a hammer and a tape clamping device operative at the conclusion of a taping operation to clamp the tape at separate 50 points, means for tensioning the tape between said points, and a knife arranged to sever the tensioned tape.

5. A tape laying machine, having in combination, starting and stopping mechanism, a hammer arranged to clamp the tape to the work at the conclusion of a taping operation, a clamping device controlled by the starting and stopping mechanism to clamp the tape at a point remote from the work when the machine is stopped, means also controlled from the starting and stopping mechanism for tensioning the tape between its clamped points, and a knife for severing the tensioned tape.

6. A tape laying machine, having in com-

bination, means for applying tape to a piece of work, starting and stopping mechanism for said tape applying means, a controlling device for said starting and stopping mechanism, and tape clamping means for holding the end of the tape at a point removed from said tape applying means at the conclusion of a taping operation arranged to be operated when said controlling device is moved to stop the machine.

7. In a tape laying machine, means for directing tape to its point of application upon a piece of work, severing mechanism including a swinging knife located normally above the path in which the tape is directed, and means for successively lowering the knife bodily and swinging it to sever the tape.

8. In a tape laying machine, means for directing tape to its point of application upon a piece of work, severing mechanism including a knife movable widthwise across the path in which the tape is directed and located normally out of said path, and means for first moving the knife bodily toward the tape and then for imparting to it a severing stroke widthwise across the path of the tape.

9. In a tape laying machine, severing mechanism including a knife, a pivotally mounted knife-carrying arm, a plunger movable in a path adjacent to the arm and having a pin and slot connection with said arm, a spring for moving the plunger in one direction and treadle controlled means for moving it in the other.

10. A tape laying machine, having in combination, tape feeding and pressing devices, a tape severing knife, a work support movable toward and from said tape feeding and pressing device, and a single treadle for controlling the position of the work support and for controlling the action of the severing knife.

11. A tape laying machine, having in combination, tape feeding and pressing devices, a tape severing knife, a work support constructed and arranged to be maintained in position adjacent to said tape feeding and pressing devices to present the work thereto, and a single treadle operable upon a single movement both to release said work support from said position of presentation and to cause said knife to cut the tape.

12. A tape laying machine, having in combination, tape feeding and pressing devices, an oppositely disposed work support movable bodily toward said devices to present the work thereto, an adjustable stop for determining the operative position of the work support, a treadle actuated cam, and yielding connections between said cam and work support for moving said work support toward said tape feeding and pressing devices.

13. In a machine for applying pressure progressively along a work piece, a work support, means cooperating therewith for press-

- ing the work piece, means for causing relative separation and approach of said pressing means and said support to facilitate the insertion of an untreated work piece therebetween, and means connected with said last-mentioned means arranged to cause said pressing means and work support yieldingly to press the work when brought together.
14. A machine for applying pressure progressively along a work piece having, in combination, pressing means, a work support movable toward and from said pressing means, means movable in one direction to cause said support to approach said pressing means and to allow said support to recede from said pressing means when moved in the opposite direction, and connections between said support and said means for causing said support yieldingly to sustain the work against the pressure of the pressing means.
15. In a machine for applying pressure progressively along a work piece, pressing means, a work support movable toward and away from said pressing means, means for controlling the movement of said work support, means for adjustably limiting the proximal position of the work support with respect to the pressing means, and connections between said support and said means for controlling the movement of said support constructed and arranged to cause the support yieldingly to sustain the work against the pressure of the pressing means.
16. In a machine for applying pressure progressively along a work piece, pressing means, a work support, means for yieldingly sustaining said work support against the pressure of said pressing means, and means connected with said last-mentioned means operable in one direction to move said support toward said pressing means and in the other to allow their separation.
17. In a machine for applying pressure progressively along a work piece, pressing means, a work support, a cam movable to cause a movement of the work support toward the pressing means, and means operated by said cam for yieldingly sustaining the work support against the pressure of said pressing means.
18. In a machine for applying pressure progressively along a work piece, pressing means, a work support, a treadle-operated cam for moving said work support toward said pressing means, means for limiting said movement of the work support, and yielding connections between said cam and said work support.
19. In a machine for applying pressure progressively along a work piece, a work support, means movable toward said support to press a work piece therebetween, a cam movable in one direction to cause a separation of said work support and pressing means and in the other to cause an approach thereof to facilitate insertion of an untreated work piece therebetween, and means for yieldingly sustaining said work support against the pressure of said pressing means disposed between said support and said cam whereby the separation of the support and pressing means is effected without stressing said yielding means.
20. In a machine for applying pressure progressively along a work piece, in combination, a work support, means cooperating therewith to press a work piece inserted therebetween, said support comprising a post, a cam for moving said work support toward said pressing means, and a sleeve mounted to slide on said post and operated by said cam, and yielding means connecting said sleeve and said post whereby said work support is caused yieldingly to hold the work against the pressing means.
21. A machine having a work support and pressing means cooperating therewith, means for operating said pressing means to press a work piece against said support and to cause a feed movement of the work piece, means for yieldingly sustaining said work support against the pressure of said pressing means, and means operable in one direction to move said support and its sustaining means bodily toward said pressing means and in another direction to allow the separation of said support and said pressing means.
22. A machine having a work support and cooperating pressing means, means for operating said pressing means to cause it to press a work piece against said support and to cause a feed movement thereof over the support, means movable in one direction to cause a movement of the work support toward said pressing means and movable in another direction to allow the work support to recede from said pressing means, and means moved bodily by said last-mentioned means for yieldingly sustaining the work support against the pressure of said pressing means.
23. A tape laying machine, having in combination, tape feeding and pressing devices, an oppositely disposed work support comprising a post, a sleeve having a lost motion connection with the post, a spring interposed between the post and sleeve, a treadle actuated cam acting through the sleeve to move the work support toward said tape feeding and pressing devices, and means for adjustably limiting such movement of the post.
24. In a tape laying machine, a work feeding foot having a work engaging face, a tape feeding foot carried by the work feeding foot and extending transversely beyond the latter so as to act upon the tape at one side of the line of work feed.
25. In a tape laying machine, a feed foot having a work engaging portion, and a tape engaging portion located at one side thereof relatively to the direction of feed, said por-

tions of the feed foot acting to advance simultaneously the work and the tape, and means for rendering said work feeding portion inoperative, whereby the tape feeding portion may act to feed the work through the tape superposed thereon.

26. In a tape laying machine, a combined work and tape feeding foot comprising a block having a tape feeding portion, a work feeding dog pivotally mounted on one side 10 of the block, and an adjustable stop for determining the position of said feed dog whereby it may be rendered operative or inoperative for feeding the work.

27. In a tape laying machine, a swinging work support, a feed foot, means for operating said feed foot to press the work against said support and impart a movement to the work and the support in the direction of feed, and means for urging said support in a direction opposite to that of the feed of the work whereby the work support is returned to its initial position at the end of the feeding movement.

28. In a tape laying machine, an oscillating feed foot, a work support movable bodily to present the work to the action of the feed foot and having a portion arranged to move with the feed foot during the feeding movement thereof, and means for causing the said portion of the work support to return to its initial position at the end of the feeding movement.

29. A tape laying machine, having in combination, treadle controlled starting and stopping mechanism, work feeding and pressing devices operatively associated therewith, a work support movable from said work feeding and pressing devices to facilitate insertion 40 of the work, and movable toward said devices to present the work to said feeding and pressing devices, a tape cutting knife, and treadle mechanism for controlling the position of the work support and the action 45 of the tape-cutting knife.

30. A tape laying machine, having in combination, work feeding and pressing means, a tape cutting knife, resilient means for maintaining said knife normally in a position 50 at the extremity of its cutting stroke at one side of the tape, and means for moving the knife into a position of readiness for its cutting stroke at the other side of the tape prior to a taping operation.

31. A tape laying machine, having in combination, work feeding and pressing means, a tape cutting knife, treadle controlled mechanism for maintaining the knife in an inoperative position while the machine is at rest, and means acting when the machine is started 60 for positioning the knife preparatory to making a cut, the treadle controlled mechanism actuating the knife subsequently in its cutting stroke.

32. A tape laying machine, having in com-

bination, work feeding means, a hammer movable in a yielding manner to press the tape upon the work, and a work supporting table movable toward and from the hammer.

33. A tape laying machine having, in combination, means for feeding tape and work and for pressing the tape upon the work, and a work support for holding the work against the pressure of said feeding and pressing means, said work support being formed in two parts each having a work engaging surface, one of said parts being constructed and arranged to partake of the feeding movement of the work and the other of said parts being maintained stationary with respect to the feeding movement of the work.

34. A tape laying machine having, in combination, means for feeding a piece of work, means for pressing adhesive tape upon the work, and a work support formed in two parts each having a work engaging surface, one of said parts being constructed and arranged to support the work against the pressure of said feeding means and to move with said feeding means in the direction of feed of the work, and the other of said parts being constructed and arranged to support the work against the pressure of said pressing means and to remain stationary with respect to the feeding movement of the work.

35. A tape laying machine having, in combination, a work feeding foot, a hammer for pressing adhesive tape upon the work, and a work support formed in two parts, one of said parts being constructed and arranged to support the work against the pressure of said feed foot and to move with said feed foot in the direction of feed of the work, and the other of said parts being constructed and arranged to support the work against the pressure of said hammer and to remain stationary with respect to the feeding movement of the work.

36. A tape laying machine having, in combination, means for feeding tape and work and for pressing the tape upon the work, and a work support movable bodily to present the work to the action of said feeding and pressing means, said work support being formed in two parts for supporting the work at two points respectively, one of said parts being movable in the direction of feed of the work and the other said part being stationary with respect to the direction of feed of the work.

In testimony whereof I have signed my name to this specification.

WILLIAM THOMAS BUCKINGHAM ROBERTS.
